*John H. Abbott
A.C. Davis*

United States Patent Office.

JOHN T. WEBSTER, OF NEW YORK CITY, AND ALBERT E. POWERS, OF LANSINGBURG ASSIGNORS TO DEBORAH POWERS, ALBERT E. POWERS, AND NATHANIEL E.
POWERS, OF LANSINGBURG, NEW YORK.

Design No. 4,344, dated September 6, 1870.

DESIGN FOR FLOOR OIL-CLOTHS.

The Schedule referred to in these Letters Patent and making part of the same

To all whom it may concern:

Be it known that we, JOHN T. WEBSTER, of the city, county, and State of New York, and ALBERT E.
POWERS, of Lansingburg, Rensselaer county, and state aforesaid, have invented or produced a new and original Design for Floor Oil-Cloths or other fabrics, which is fully shown upon the drawings accompanying his specification, which we hereby declare to be a part thereof; and What is claimed as our invention, and is desired to be secured by Letters Patent of the United States is—

The design for floor oil-cloths, as shown on said drawings and herein described.

JOHN T. WEBSTER.
A. E. POWERS.
